UNITED STATES PATENT OFFICE.

JOHN GRAHAM, OF NEW YORK, N. Y.

DESIGN FOR GIMP.

SPECIFICATION forming part of Design No. 11,727, dated April 13, 1880.

Application filed January 29, 1880. Term of patent 7 years.

To all whom it may concern:

Be it known that I, JOHN GRAHAM, of the city, county, and State of New York, have invented a new and original Design for Gimp and Similar Fabrics, of which the following is a specification.

My present design consists in pairs of cross-shaped figures and an intervening stripe extending lengthwise of the gimp or other fabric. Such longitudinal stripe may be composed of alternate sections of different colors or shades, and additional longitudinal stripes may be used in proximity to the edges of the gimp or other fabric.

The accompanying drawing represents a face view of a piece of gimp embellished with my new design.

A designates the gimp, which may have the so-called "feathered edges" or plain edges. B B' designate pairs of cross-shaped figures arranged in pairs side by side. C C' designate a longitudinal central stripe, here shown as composed of alternate sections, C and C', of different colors or shades, and extending lengthwise of the gimp between the cross-shaped figures B and B' of the several pairs of such figures. These cross-shaped figures may be

formed by suitably displaying on the face of the gimp sections of certain of the warp-threads, and when so delineated will have a jagged 30 outline. D designates narrow stripes extending lengthwise of the gimp close to its edges.

What I claim as my invention, and desire to secure by Letters Patent, is—

1. The design for gimp and other fabrics, 35 consisting of pairs of cross-shaped figures B B' and an intervening stripe extending lengthwise of the gimp or fabric.

2. The design for gimp and other fabrics, 40 consisting of pairs of cross-shaped figures B B' and an intervening stripe extending lengthwise of the fabric and composed of sections C C' of different shades.

3. The design for gimp and other fabrics, 45 consisting of pairs of cross-shaped figures B B', an intervening stripe extending lengthwise of the fabric, and other stripes, D, extending lengthwise of the fabric and close to the edges thereof.

JOHN GRAHAM.
